COUPLER

Edmund P. Kinne and Frank H. Kayler, Alliance,
Ohio, assignors to American Steel Foundries,
Chicago, Ill., a corporation of New Jersey

Application May 4, 1939, Serial No. 271,803

20 Claims. (Cl. 213—154)

This application is a continuation-in-part of our copending application, Couplers, Serial No. 123,346, filed in the United States Patent Office February 1, 1937.

Our invention relates to railway car couplers and more particularly to a design of railway car coupler interchangeable with the present standard A. A. R. coupler; it comprehends an improvement on the controlled slack design of coupler shown in Patent No. 2,098,207, issued November 2, 1937, in the name of Frank H. Kayler.

As commonly applied in railway service the great majority of car couplers have a certain amount of play between mated couplers, this being commonly called free slack. The clearances resulting in this free slack are necessary in the standard coupler arrangements to permit of couplers angling horizontally and vertically. A certain amount of clearance has also been provided in such arrangement to permit satisfactory operation of the parts in coupling.

In the above mentioned Kayler Patent No. 2,098,207, approximately two thirds of this free slack has been changed to controlled slack through use of the resilient cushion type knuckle. The remaining clearance between the knuckle face and the face of the mating coupler is retained and is necessary to facilitate coupling.

A certain amount of looseness in the fit of the various coupler parts is also necessary in order that they may be movable with respect to each other, and that they may be interchangeable without being held to unnecessarily close manufacturing tolerances. This is particularly true of railway car couplers in which the parts are used as cast and are not subject to machining operations.

As the various parts of the couplers are worn in by service, additional slack develops, of course, between the parts where rubbing takes place. It has been found that this looseness results in noise in the operation of the couplers, especially when cars are running with little or no pull or buffing pressures between the couplers.

On certain types of equipment this development of slack is not particularly objectionable until it has developed to a point affecting safety, or where coupling becomes uncertain or inefficient. On other types of equipment, however, such as passenger trains, it is desirable to eliminate as far as possible the play between parts in order to facilitate the handling of the train in a manner that is conducive to the comfort of the passenger. This requires the elimination of noise as far as practicable and reduction of shocks and jerks

which often develop in a train with uncontrolled slack.

It is an object of the present invention to so design a railway car coupler that wear between the parts will not result in free slack between mated couplers.

Our invention comprehends a form of control for so-called free slack in a coupler which will be applicable to present standard car construction and in particular to standard passenger car types.

The present invention provides for control of all free slack between couplers, including control of the small amount of free slack which remains in couplers fitted with cushion type knuckles, as covered by Kayler Patent No. 2,098,207.

A further purpose of our invention is to provide such a design of slack-free coupler while, at the same time, maintaining the feature of interchangeability with present standard car couplers in use.

Our invention also comprehends a slack-free car coupler wherein all of the parts will be interchangeable with the corresponding parts in present standard A. A. R. coupler designs.

A still further purpose of our invention is to so design a slack-free coupler that none of the parts will require machining and that such parts may be produced under the same manufacturing conditions as coupler designs at present in use.

Our invention also comprehends a car coupler which will automatically compensate for loosening between the parts due to the normal seating therebetween or to wear which develops under ordinary conditions of use.

Our invention likewise comprehends a design of coupler wherein abutting parts of two mated or coupled couplers will at all times be under compression against each other, thus preventing jolts and jars between them with the concomitant noise.

Another object of our invention is an improvement in the ability to couple mated couplers from positions of increasing lateral angularity.

With these and various other objects in view, our invention may consist of certain novel features of construction and operation as will be more fully described and particularly pointed out in the specification, claims and drawings appended hereto.

In the drawings which illustrate embodiments of the device and wherein like reference characters are used to designate like parts—

Figure 1 is a top plan view of a car coupler embodying our invention, the tail portion of the coupler being cut away;

Figure 2 is a fragmentary front elevation of the car coupler shown in Figure 1 illustrating the lug structure on the knuckle side of the coupler head;

Figure 3 is a fragmentary elevational view from the guard arm side of the coupler structure shown in Figure 1, with the plunger removed from the assembly;

Figure 4 is a fragmentary front elevational view of the guard arm side of the coupler;

Figure 5 is a sectional view through the guard arm side of the coupler shown in Figure 1, the section being taken substantially in the plane indicated by the line 5—5 of Figure 1;

Figure 6 is a section similar to that shown in Figure 5, the section being taken also through the guard arm but forward of that shown in Figure 5 and substantially in the plane indicated by the line 6—6 of Figure 1;

Figure 7 is a side elevation of the plunger;

Figure 8 is an end view of the plunger;

Figure 9 is a plan view of the plunger associated with the guard arm of the coupler;

Figure 10 is a section through one wall of the plunger, the section being taken substantially in the plane indicated by the line 10—10 of Figure 9;

Figure 11 is a top plan view of two car couplers embodying our invention at the point of coupling under conditions of lateral angling approaching the maximum gathering range;

Figure 12 is a top plan view of two couplers embodying our invention in normal pulling position;

Figure 13 is a view similar to Figure 12 except that the couplers are angled laterally the maximum amount permitted by the contours under coupled conditions.

Figure 14 is a top plan view of a modified form of car coupler embodying our invention;

Figure 15 is a sectional view through the guard arm portion of our invention shown in Figure 14 and taken substantially in the planes indicated by the line 15—15 of Figure 14;

Figure 16 is a top plan view of two couplers of the modification shown in Figure 14 in normal pulling position, and Figure 17 shows them angled laterally the maximum amount permitted under coupled conditions; and

Figure 18 is a side elevation of two couplers of the modification shown in Figure 14 in normal coupled position.

Describing our novel structure in more detail, the coupler head generally designated 2 (Figure 1) comprises the knuckle 4, of the improved design described in detail in the above mentioned Kayler Patent 2,098,207, pivotally mounted as at 6 in the manner of the present A. A. R. standard; and comprises also the guard arm 8 having a contour conforming in general to that of the present A. A. R. standard coupler except for the slight variance near the end of the guard arm contour as shown at 10.

On the knuckle side of the coupler head is integrally cast the lug 12 recessed as at 14 and reinforced by the upper and lower ribs 16 and 18. The outer portion of the lug 12 projects forwardly as at 20 for engagement with the opposing face of the guard arm plunger, hereinafter more fully described, when two couplers are coupled (Figure 12).

The guard arm 8 is considerably enlarged as compared with the present A. A. R. standard and has incorporated therein a spring pocket 22 having the upper and lower cavities 24 and 26 respectively for the reception of coil springs 28 and 30. The centrally located horizontal reinforcing wall 32 divides the spring pocket 22 into the above mentioned upper and lower cavities. The springs 28 and 30 are positioned in their respective cavities by the bosses 34, 34 at the bottoms of the cavities and also by the central reinforcing wall 32 as well as by the top and bottom walls 36 and 38 of the guard arm plunger generally designated 40 (Figures 7 to 10, inclusive). The springs 28 and 30 are retained in position at their forward ends against the front wall of the guard arm plunger 40 by the centering bosses 42, 42 and the guard arm plunger is retained in position after assembly with the springs 28 and 30 under some initial compression by the rivet 44 against which abut the lugs 46, 46 integrally formed on the rear end of the guard arm plunger.

The guard arm plunger 40 is shown in Figure 1 in its normal position after assembly with the springs 28 and 30 under some initial compression and urging the plunger outwardly, said plunger being retained in the position shown by the abutment of the lugs 46 (Figure 9) against the rivet 44. In normal uncoupled position shown in Figure 1, it will be observed that the outer face 48 of the guard arm plunger 40 extends somewhat beyond the forward extremity 50 of the guard arm 8. When coupled and in normal pulling position (Figure 12) the plunger is depressed somewhat from the position shown in Figure 1 by engagement with the projecting end 20 of the lug 12 on the opposing coupler. Maximum rearward movement of the guard arm plunger 40 is limited by abutment of the forward extremity 50 of the guard arm against the recess at 14 on the lug 12 of a mating coupler as at 54 (Figure 13). This maximum rearward movement of the plunger occurs under conditions of lateral angling when in coupled position as shown for example in Figure 13.

The guard arm plunger 40 is shown in detail in Figures 7 to 10, inclusive. It is a one-piece structure, generally U-shaped in form, having top and bottom walls 56 and 58 respectively, cylindrical in shape on their inner faces as at 59 (Figure 10) to conform to the shape of the enclosed springs 28 and 30; and a front wall 60 on the inner face of which are formed the bosses 42, 42 serving as positioning means for the outer ends of the coil springs 28 and 30 as previously described. Integrally joining the top and bottom walls 56 and 58 and the front wall 60 is the lateral wall 62 and the horizontal reinforcing rib 64. Centrally located on the outer wall at the forward end of the plunger is the positioning lug 66 which may be received within the similarly shaped slot 68 (Figure 3) formed in the forward edge of the outer wall 70 of the guard arm 8. Along the edge of the plunger 40, opposite the positioning lug 66, is formed the slightly raised lip 72 serving to increase slightly the gathering range under conditions where couplers are offset in a horizontal direction, and tending to retain engagement with the projecting end 20 on the lug 12 of a mating coupler.

In operation of our improved coupler, control of the contour slack is accomplished in the following manner. As the mated couplers are forced into closer engagement from the normal

pulling position shown in Figure 12, the first portion of the movement is controlled by the pressure of the plungers 40, 40 on the respective couplers having engagement with the opposed projecting ends 20, 20 on the lugs 12, 12. After such preliminary movement, the buffing plates 74, 74 of the mating knuckles engage the mating coupler faces as at 76, 76 and greatly increase the force controlling the remaining movement permitted by the contour. The total force then operative is that provided by the cushion type knuckles, as described in the above mentioned Kayler patent, plus the force exerted by the guard arm plungers as hereinafter described.

After the buffing plates 74 come into engagement with the mating coupler faces, the force required to move the couplers closer together is greater than the force normally required under present standard conditions to start movement of the conventional draft gear used in connection with such couplers, thus the slack controlled facilities of our improved coupler become as effective in controlling contour slack as if the contour movement was positively limited by unresisting means such as is in use on a certain type of couplers generally known as tight-lock couplers.

From the above and from the consideration of the drawings shown herewith, particularly Figures 1 and 14, it will be apparent to those skilled in the art that the relatively small guard arm springs supporting the guard arm buffer are of small capacity in comparison with the springs supporting the cushion knuckle. In actual practice we have provided several times as great capacity per inch of travel in the knuckle springs as compared with the springs in the guard arm. It will be appreciated that the comparatively low build up of capacity in proportion to the travel in the guard arm springs is necessary to permit the normal coupling operation in which it would not be practical to compress springs of the capacity referred to in the above mentioned Kayler cushion knuckle wherein the initial capacity of the cushioning springs is described as approximately equal to that secured at the beginning of travel in standard draft gears for passenger cars. In other words, the springs in the cushion knuckle, upon application are compressed a large proportion of their travel and, therefore, further compression of these springs is resisted by like proportion of their solid capacity. On the other hand, the springs in the guard arm are compressed a relatively small amount upon application, and only a minor proportion of their travel and, therefore, offer resistance equal to a relatively small proportion of their solid capacity. In addition, the solid capacity of the springs in the guard arm is relatively small as compared with the solid capacity of the cushion knuckle springs.

Straight line coupling under normal conditions may take place between two couplers embodying my invention or between one such coupler and an A. A. R. standard coupler without compression of the cushion knuckle buffering plate, but in every coupling operation between two couplers embodying our invention, some compression of the guard arm plungers necessarily takes place. For this reason also, the guard arm plungers must be relatively free in movement and supported by springs of relatively small capacity as compared with the springs supporting the cushion knuckle. If the guard arm plunger spring were too stiff, the coupling action would be prevented

and the mating couplers would be forced away from each other resulting in failure to couple.

As shown in Figure 11, the guard arm plungers, in addition to operating to control the contour 5 slack, act to bring the couplers into axial alignment when being coupled from an angular position. In the case particularly of long shank couplers of the present standard design, satisfactory coupling up to the theoretical maximum 10 coupling angle is not practical because of buckling or jack-knifing of the couplers, as it is commonly called, to a position of angularity beyond the coupling range. This buckling is due to the fact that the line of force from one coupler butt pivot to the other passes outside of the contact 15 point of the knuckle with the mating coupler face.

As shown in Figure 11, the contact of the plunger face 48 with the projecting end 20 of the lug 12 lies a greater distance from the coupler center line than is the case in standard 20 couplers so that under full angled conditions the line of force shown at 78 between the pivot point 80 of one coupler and the pivot point 82 of the other coupler, along which the couplers are moving toward each other, lies inside of the contact 25 point at 84. Movement of the plunger is resisted by sufficient pressure of the springs 28 and 30 to cause the couplers to be moved over into axial alignment, thereby accomplishing the coupling or locking of the couplers and bringing them into the position shown in Figure 12, thus, with our improved type of coupler, the coupling operation can be accomplished from greater 30 angles and in a more positive manner than is possible with couplers of the present standard design.

Where the coupling operation is to be effected between cars having a limited provision for lateral angling or between two cars on a sharp curve, coupling can be effected under greater angularity than is possible with the present standard couplers since the pressure exerted in the first contact point 84 between the plunger on one 35 coupler against the lug on a mating coupler acts to prevent the couplers from buckling and to keep them within the angularity range of coupling.

Figure 13 illustrates how our improved coupler may angle the full amount provided for in the 40 present standard A. A. R. coupler. When this occurs, the guard arm plunger of one coupler and the knuckle buffering plate of the mating coupler are both compressed as shown in Figure 13. When conditions permit, these pressures act to 45 return the couplers to axial alignment and, thus, tend to decrease the pressure of the wheels against the outside rail on a curve.

The modification shown in Figures 14 to 18, inclusive, is similar in function to that previously 50 described, but differs therefrom in that this modification is arranged to couple with the tight lock coupler relatively recently adopted as a standard on American railroads. In order to accommodate 55 coupling with said tight lock standard, the modification at present under discussion is constructed with a relatively long guard arm. The parts of this modification are similar in function to those of that previously described with certain differences of detail, more particularly referred to 60 hereafter.

The coupler head 90 comprises the pivoted 65 cushion knuckle 92 of the form above referred to and described more particularly in Kayler Patent 2,098,207, said knuckle being pivotally mounted 70 as at 94 in the manner of the present A. A. R.

standard. The coupler head comprises also the guard arm 96 having a contour conforming in general to that of the present A. A. R. standard to about the point indicated at 98.

On the knuckle side of the coupler head is integrally cast the lug 100 recessed as at 102, said recess being defined by the rear wall 104 and the top and bottom flanges 108 and 110 (Figure 18), said rear wall being reinforced by spaced horizontal ribs 106, 108 (Figure 18). The said rear wall 104 of the recess 102 affords abutment for the guard arm plunger of a mating coupler, said plunger being afforded vertical movement in the space between the before mentioned top and bottom flanges 108 and 110 in order to accommodate coupling between two couplers at varying levels.

The guard arm 96 is relatively large and elongated and has the generally rectangular cavity 112 extending throughout its length and open at the forward end thereof for reception of the slidable hollow plunger 113, which is seated therein. A relatively long coil spring 114 is housed at the forward end within the hollow plunger 113 and at its rear end within the guard arm cavity 112 abutting the base of said cavity as at 116 against which it is positioned by the lug 118. Also housed within the cavity 112 is the relatively short spring 120 surrounding the inner end of the spring 114 and having abutment as at 122 with the inner end of the plunger 113. The outer side of the plunger 113 is notched as at 124 and 126 to form stop means for engagement with the plunger retaining rivet 128 positioned centrally of said guard arm. The capacity of the springs engaging the guard arm plunger 113 is relatively small in comparison with the capacity of the springs in abutment with the buffing plate 74 of the cushion knuckle, thus accommodating normal coupling as above described.

Figure 16 shows the normal coupler position of mated couplers such as those just described, and Figure 17 shows the same couplers under maximum lateral angling when coupled. From a consideration of Figures 16 and 17, it will be clear that in normal coupled position the guard arm plungers 113 are only slightly compressed. Rapidly increasing resistance is offered thereby as the couplers are increasingly angled with respect to each other until the plunger of one coupler is compressed a maximum as seen at 130 (Figure 17). At the same time, one of the cushion knuckles is likewise compressed as indicated at 132 and the force of the springs thus compressed retains the opposed coupler heads in tight relationship with each other preventing play therebetween and lost motion. When conditions permit, these pressures also act to return the couplers to axial alignment as described for the previous modification. From a consideration of Figure 16 it will also be apparent that very slight relative movement can occur between the couplers in normal coupled position before the cushion knuckle is brought into operation in addition to the guard arm plungers due to the slight space or clearance permitted between each cushion knuckle as at 134 and the opposing face of the coupler head.

Vertical angling in the contour between mated couplers of our improved design is provided for as with present standard couplers and, in such a movement, partial compression of the guard arm plungers occurs as well as partial compression of the top or the bottom of the knuckle buffing plates. Our improved coupler is operative in conjunction with all present standard designs

of A. A. R. couplers, but when a coupler of the present A. A. R. standard is connected to our improved design, the slack control feature is limited to that provided in the single cushioned knuckle. The slack control features shown in our improved coupler design are not limited to couplers of the present A. A. R. standard or to couplers interchangeable therewith, but may be applied to any knuckle type coupler.

It is to be understood that we do not wish to be limited by the exact embodiments of the device shown which are merely by way of illustration and not limitation as various and other forms of the device will of course be apparent to those skilled in the art without departing from the spirit of the invention or the scope of the claims.

We claim:

1. In a car coupler, a head, a resilient knuckle pivoted in said head, a lug integrally formed with said head, said lug comprising a projecting portion and a recessed portion, a guard arm opposite said knuckle, said guard arm having a projecting portion and a recessed portion, a cavity in said guard arm, and a resiliently mounted plunger in said cavity, said plunger having a buffing face normally extending outwardly of said projecting portion of said guard arm and being retractable under buff of an opposing coupler to a position where said face lies substantially within the plane of said recessed portion of said guard arm, said resiliently mounted plunger having a relatively light capacity per unit of travel as compared with said resilient knuckle, whereby the coupling operation may be effected without excessive shock.

2. In a lateral angling car coupling, the combination of coupler heads having knuckles pivotally mounted therein, guard arms opposite said knuckles, sockets adjacent said knuckles, relatively high capacity buffing means resiliently mounted in said knuckles, and relatively low capacity buffing means resiliently mounted in said guard arm, said last mentioned buffing means having cooperation respectively with said opposed sockets and said first mentioned buffing means being free of cooperation with the opposed couples when said coupler heads are in normal pulling position, said sockets affording limited vertical movement for the buffing means received therein.

3. In a car coupling characterized by lateral angling, mated couplers comprising coupler heads, pivoted knuckles, sockets adjacent said knuckles, guard arms opposite said knuckles, buffing means resiliently mounted in said guard arms under relatively light compression, and buffing means mounted in said knuckles under relatively heavy compression, said buffing means under light compression being adapted to cooperate with the opposing sockets in the normal coupling operation, and both types of said buffing means being adapted to offer resistance to lateral angling, said sockets affording limited vertical movement of the buffing means received therein.

4. In a railway coupling characterized by lateral angling, the combination of mated coupler heads, knuckles pivoted therein, guard arms opposite said knuckles, means resiliently mounted in each of said guard arms and in each of said knuckles, and brackets laterally mounted on said heads adjacent said knuckles, both of said guard arm means being under compression when said couplers are in normal pulling position by engagement with the opposed brackets, said knuckle

resilient means having relatively high capacity per unit of travel as compared with said guard arm resilient means.

5. In a railway coupler characterized by lateral angling, the combination of a coupler head, a resilient knuckle pivoted therein, a guard arm comprising a projecting member and a recessed portion, a cavity in said guard arm, and means resiliently mounted in said cavity, said means normally extending outwardly of said projecting member and being retractable to a position coinciding substantially with said recessed portion, said resiliently mounted means having a relatively light capacity per unit of travel as compared with said resilient knuckle, whereby the coupling operation may be effected without excessive shocks.

6. In a car coupler, a coupler head, a pivoted resilient knuckle, a lug formed on said head laterally of said knuckle, a guard arm opposite said knuckle, said guard arm having a recessed portion, a cavity in said guard arm, and a plunger resiliently mounted in said cavity under relatively light compression as compared with the compression of said resilient knuckle and as compared with the forces employed in the normal coupling operation, said plunger normally extending beyond said guard arm and being retractable therein under buff substantially to the position of said recessed portion.

7. In a car coupler, a coupler head, a pivoted resilient knuckle, a lug on said head laterally of said knuckle, a recessed portion on said lug, a guard arm opposite said knuckle, said guard arm having a recessed portion, a cavity in said guard arm, and a plunger resiliently mounted in said cavity under relatively light compression as compared with the compression of said resilient knuckle and as compared with the forces employed in the normal coupling operation, said plunger normally extending beyond said guard arm and being retractable therein under buff substantially to the position of said recessed portion.

8. In a coupling, the combination of coupler heads having pivoted knuckles, lugs mounted on said heads adjacent said knuckles, guard arms on said heads opposite said knuckles, and buffing means resiliently mounted in said knuckles and in said guard arms, said guard arm buffing means having relatively light capacity springs as compared with said knuckle buffing means, certain of said buffing means having cooperation when said coupler heads are in normal pulling position and other of said buffing means having cooperation under lateral angling.

9. In a car coupling the combination of coupler heads, knuckles pivoted therein, guard arms opposite said knuckles, means resiliently mounted in said knuckles, and other means resiliently mounted in said guard arms, both of said guard arm means having cooperation with the opposing coupler head when in normal pulling position and one of said guard arm means being free of cooperation therewith under certain conditions of lateral angling, said knuckle resilient means having relatively high capacity per unit of travel as compared with said guard arm resilient means.

10. In a lateral angling car coupling, the combination of coupler heads having knuckles pivotally mounted therein, guard arms opposite said knuckles, sockets adjacent said knuckles, relatively high capacity buffing means resiliently mounted in said knuckles, and relatively low capacity buffing means resiliently mounted in said guard arms, said last mentioned buffing means

having cooperation respectively with said opposed sockets and said first mentioned buffing means being free of cooperation with the opposed couplers when said coupler heads are in normal pulling position.

11. In a car coupling characterized by lateral angling, mated couplers comprising coupler heads, pivoted knuckles, sockets adjacent said knuckles, guard arms opposite said knuckles, buffing means resiliently mounted in said guard arms under relatively light compression, and buffing means mounted in said knuckles under relatively heavy compression, said buffing means under light compression being adapted to cooperate with the opposing sockets in the normal coupling operation, and both types of said buffing means being adapted to offer resistance to lateral angling.

12. In a car coupling, the combination of coupler heads having knuckles pivotally mounted therein and guard arms opposite said knuckles, relatively soft buffing means resiliently mounted in said guard arms, and other relatively stiff buffing means resiliently mounted in said knuckles, said first mentioned buffing means having cooperation respectively with the mated couplers when said coupler heads are in normal pulling position and said last mentioned buffing means being free of cooperation therewith.

13. In a car coupling, the combination of coupler heads, knuckles pivoted therein, guard arms opposite said knuckles, means resiliently mounted in said knuckles, and other means resiliently mounted in said guard arms, said knuckle resilient means having relatively high capacity per unit of travel as compared with said guard arm resilient means, certain of said first and last mentioned means having cooperation with the opposing coupler head under conditions of maximum lateral angling.

14. In a car coupling, mated couplers comprising coupler heads, pivoted knuckles, guard arms, buffing means resiliently mounted in said guard arms and said knuckles, said buffing means in said knuckles having a relatively high capacity per unit of travel as compared with the relatively light capacity of said buffing means in said guard arms, whereby the normal coupling operation may be effected by compression of said relatively light capacity buffing means and without substantial movement of said relatively high capacity buffing means.

15. In a car coupling, mated couplers comprising coupler heads, pivoted resilient knuckles, guard arms opposite said knuckles, brackets adjacent said knuckles, and plungers resiliently mounted in said guard arms and said knuckles, the plungers in said guard arms being mounted to yield under relatively light compression and those in said knuckles to resist relatively heavy compression, whereby said guard arm plungers may have movement in the normal coupling operation and said knuckle plungers may resist such movement except under conditions of relatively heavy shock.

16. In a car coupling, mated couplers comprising coupler heads, pivoted knuckles, guard arms opposite said knuckles, brackets adjacent said knuckles, and plungers resiliently mounted in said guard arms and said knuckles, said knuckle plungers affording relatively high resistance to compression as compared to said guard arm plungers, said guard arm plungers being adapted to have engagement with mating couplers in the normal coupling operation, where-

by said normal coupling operation may be effected without excessive shock.

17. In a coupling characterized by lateral angling, mated couplers comprising coupler heads having pivoted knuckles and opposed guard arms, buffing means mounted in said guard arms under relatively light compression, and buffing means mounted in said knuckles under relatively heavy compression, said guard arm buffing means being adapted to engage and be compressed by the opposing coupler heads in the normal coupling operation, and certain of both types of buffing means being adapted to resist lateral angling.

18. In a car coupling, the combination of coupler heads having pivoted knuckles, guard arms, and buffing means resiliently mounted in said guard arms and said knuckles, said guard arm buffing means having relatively light capacity as compared with said knuckle buffing means and being adapted to be compressed in the coupling operation, and said knuckle buffing means hav-

ing a relatively high capacity and adapted to resist compression in the coupling operation.

19. In a car coupler having a pivoted knuckle and a guard arm, buffing means resiliently housed in said knuckle and in said guard arm, said means being retractile in their respective housings to positions within the normal contour of said parts, said knuckle resilient means having relatively high capacity per unit of travel as compared with said guard arm resilient means.

20. In a car coupler, a head, a knuckle pivoted therein, a guard arm, buffing means of relatively light capacity mounted in said guard arm and buffing means of relatively heavy capacity mounted in said knuckle, whereby the normal coupling operation may be effected by compression of said relatively light buffing means without substantial movement of said relatively heavy capacity buffing means.

EDMUND P. KINNE.
FRANK H. KAYLER.
